(57) **CLAIM**

The ornamental design for an ultrasonic diagnosis apparatus controller, as shown and described.

DESCRIPTION

FIG. 1 is a front, left side and bottom perspective view of an ultrasonic diagnosis apparatus controller, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

1 Claim, 4 Drawing Sheets

FIG. 2

FIG. 3

FIG. 4

FIG. 5

FIG. 6

FIG. 7
